FIGURE GAUGE FOR SAW MILLS

George L. Berry, Culpeper County, Va.

Application May 27, 1955, Serial No. 511,578

5 Claims. (Cl. 143—124)

This invention relates to a figure gauge for saw mills, and has for one of its objects the production of a simple and efficient endless type of indicator for indicating the setting of the head blocks of the saw machinery to obtain the desired thickness of the timber to be sawed.

Another object of this invention is the production of a figure gauge for the set works of a saw mill wherein the gauge is so mounted as to be easily seen by the operator and which may be also swung upon its mounting so as to be brought into convenient view of an operator.

A still further object of this invention is the production of a figure gauge for saw mill set works, which is durable and efficient, and which is simple in construction, easy to manufacture, and which may be placed upon the market at a reasonable cost.

Other objects and advantages of the present invention will appear throughout the following specification and claims.

In the drawings:

Figure 1 is a front elevational view of the figure gauge, certain parts being shown in section;

Figure 2 is a top plan view of the figure gauge and its mounting;

Figure 3 is a longitudinal sectional view of the extensible gauge casing;

Figure 4 is a transverse sectional view taken on line 4—4 of Figure 3;

Figure 5 is a transverse sectional view taken on line 5—5 of Figure 3;

Figure 6 is a transverse sectional view taken on line 6—6 of Figure 3;

Figure 7 is a transverse sectional view taken on line 7—7 of Figure 3;

Figure 8 is a vertical sectional view taken on line 8—8 of Figure 1;

Figure 9 (Sheet 1) is an end view of the indicator casing.

By referring to the drawings in detail, it will be seen that 10 designates the carriage rails of the conventional type, to one of which rails is bolted or otherwise secured, the base flange 11 of an upstanding gear housing 12. The flange 11 is bolted or secured to one of the rails 10 in a position parallel to the carriage rails 10, as shown in Figures 1, 2 and 8. This gear housing 12 is provided with an upper top portion 14 which extends in an opposite direction relative to the base flange 11. This top portion 14 extends parallel and in spaced relation to the carriage rails 10. Side shield plates 15 close the sides of the gear housing 12, as shown in Figures 1, 2 and 8.

The conventional line shaft 16 extends longitudinally in spaced relation to the carriage rails 10, and is supported in the conventional manner. A V-pulley 17 is carried by this shaft 16, and a V-belt 17a passes over this pulley 17, and the pulley 18 which is carried by the auxiliary shaft 19. One end of this shaft 19 is journaled in the gear housing 12 and is journaled near its opposite end in the supporting yoke 20, which constitutes a brace for the outer end of the auxiliary shaft 19.

2

A beveled gear 21 is carried by the inner end of the shaft 19 and meshes with a beveled gear 22 which is carried by the lower end of the vertical shaft 23. The lower extremity of the vertical shaft 23 is journaled upon the supporting bracket 24 which is secured to the inner face of the gear housing 12, as is shown in Figure 1. An upstanding externally threaded collar 25 is carried by the top of the gear housing 12 and constitutes a bearing sleeve for the vertical shaft 23 which passes therethrough. A vertically extending sleeve 26 is threaded at its lower end upon the externally threaded collar 25 and is suitably lubricated by a conventional grease cup 27. The sleeve 26 may be rotated to a desired adjusted position and then locked by the set screws 28 to hold the sleeve 26 in a set position.

A cap element 29 is threaded upon the upper end of the sleeve 26, and is lubricated by means of a conventional grease cup 30. The cap member 29 is rotatable upon the upper end of the sleeve 26, and after it is adjusted to the desired position, it is locked in a set position relative to the sleeve 26 by means of a set screw 31. The cap member 29 is provided with a cavity 32 in which is located a vertical spool 33. The spool 33 is carried by the upper squared end of the shaft 23 to key the spool 33 to the shaft 23. A suitable closure 34 covers the cavity 32 to close in the parts. The cap member 29 is provided with a protruding hollow neck 35 which is preferably square in cross section.

A laterally extending hollow shank 36 constituting an indicator casing, also preferably square in cross section, is slidably fitted at one end over the neck 35, and a plurality of protruding ears 37 are carried by the shank 36 near its inner end. Threaded bolts 38 and 39 pass through these ears 37 and engage the cap member 29 to adjust the shank 36 toward and away from the cap member 29 to adjust the tension of the bolt 40 hereinafter described. The shank 36 may be locked in a set position upon the neck 35 after it is adjusted to a selected position by means of the set screws 41. The shank 36 is provided near its outer end with an abutment collar 42.

An outer spool supporting housing 43 is provided with a hollow squared neck 44 which fits over the outer end of the shank 36 and abuts the collar 42. A gate or door 45 is hinged to the outer end of the housing 43 and may be opened and closed to obtain access to the housing 43. A suitable latch 46 is provided to hold the gate or door 45 in a closed position. A spool 47 is carried by the vertical journal pin 48 of the housing 43. The housing 43 is locked in a set position upon the sleeve 36 by means of the set screws 49.

As is shown in Figure 1, the endless belt 40 is provided with a plurality of consecutive spaced numbers, such as 1 to 15, etc., throughout the length thereof. This belt 40 passes over the spools 33 and 47, and longitudinally of the housing 43, the shank 36, and into the cap member 29. The housing 43 is provided with an indicator window 50 in one side facing the operator, and the endless belt 40 is guided or threaded longitudinally of the window 50 so that the numbers or numerals upon the belt 40 may be viewed therethrough when registering with the reference index 49a thereof.

It should be noted that an operator standing in front of, and on the left side of, the carriage rails 10, looking in a forward direction when the machine is in operation, and facing the window 50 of the housing 43, may easily observe the numerals upon the belt 40, since they will be about eye level just in front of him. If desired, the housing 43, shank 46, and cap member 29, may be swung in the direction of the arrows shown in Figure 2, from the transverse normal position shown in full lines, that is, toward or away from the operator to place the device at a selected angle for convenient viewing by the oper-

ator. This operation is possible due to the fact that the cap member 29 and sleeve 26 are rotatably mounted on a vertical axis. The housing 43, sleeve 36, and cap member 29, which constitute one assembly or unit, may be locked in a set or selected position by means of the set screws 31 and 28.

It should be further noted that the line shaft 16 which sets the size of the work to be cut or sawed, regulates or drives the belt 40 through the shafts 19 and 23, thereby indicating to the operator through the window 50, the size of the work. This avoids the necessity for the operator changing his position or line of vision to read the numbers on the belt 40, since these numbers are always in front of him in a selected position.

It should also be noted that certain detail changes in the construction and arrangement of parts may be employed without departing from the spirit of the invention.

Having described the invention, what is claimed as new is:

1. A device of the class described comprising a support, a rotatable line shaft on the support, an indicator mounted on the support adjacent said line shaft, said indicator comprising a base, a vertically extending rotatable shaft projecting from the base, means for rotating said vertical shaft from said line shaft, a journal sleeve rotatable about said vertical shaft and upon said base, said indicator also including an elongated laterally and outwardly extending indicator casing carried by said journal sleeve at substantially eye level, an endless indicator belt in said casing mounted around spaced means at opposite ends of said casing to form an elongated loop the sides of which have longitudinal movement within said casing, drive means carried by said vertically extending shaft and engaging said endless indicator belt for driving said endless indicator belt so the sides of the loop travel longitudinally within said indicator casing, and said belt having consecutively arranged numerals formed peripherally of said belt and

co-operating with an index mark on said casing to indicate the position of rotation of said line shaft.

2. A device as defined in claim 1, wherein said indicator normally extends transversely of said line shaft, and means is provided to lock said indicator in a set angular selected swung position toward and away from said line shaft.

3. A device as defined in claim 1, wherein said indicator includes a cap member journaled on said sleeve, a spool fixed to said vertical shaft, a spool carried by the outer end of said casing, said belt passing around said spools, and said casing having an outer end provided with a viewing window to facilitate the viewing of the belt as it passes the window, and a reference index carried by the window to indicate the position of said belt.

4. A device as defined in claim 1, wherein said indicator casing is longitudinally adjustable, and said casing is substantially square in cross section, and means for locking said casing in a longitudinally adjusted position.

5. A device as defined in claim 1, wherein said indicator includes a cap member, said casing comprises a lateral sleeve substantially square in cross section connected to and adjustable toward and away from said cap member, said casing has an outer end longitudinally adjustable upon said sleeve, and adjustable means are interposed between said cap member and said sleeve for adjusting the sleeve toward and away from said cap member to regulate the tension of said belt.
